UNITED STATES PATENT OFFICE.

SAMUEL S. LANGFORD, OF CRAIG, NEBRASKA.

BRICK-TONGS.

SPECIFICATION forming part of Letters Patent No. 764,059, dated July 5, 1904.

Application filed March 5, 1904. Serial No. 196,664. (No model.)

To all whom it may concern:

Be it known that I, SAMUEL S. LANGFORD, a citizen of the United States, residing at Craig, in the county of Burt and State of Nebraska, have invented a new and useful Brick-Tongs, of which the following is a specification.

This invention relates to devices for carrying an object or a plurality of objects, more particularly for carrying bricks from place to place, either in removing them from the kilns, in building operations, or for any other desired purpose, and has for its object to provide a simply-constructed device which may be readily and quickly applied to and released from the object or material to be carried and employing one hand only and which may be readily adjusted to different sizes and forms of objects.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages, and the right is therefore reserved of making all the changes and modifications which fairly fall within the scope of the invention and the claims made therefor.

In the drawings thus employed, Figure 1 is a perspective view of the device detached from its load. Fig. 2 is a perspective view of the device applied. Fig. 3 is transverse section, enlarged, at 3 3 of Fig. 1.

The improved device consists of two members 10 11, having grip-plates 12 13, respectively, at their ends and preferably integral therewith and extending at right angles therefrom. The member 10 is forked at the end

opposite to its grip-plate, as at 14, and with 50 spaced transverse apertures 15 through the forked portion. The member 11 is inserted within the forked portion of the member 10 and provided with a transverse aperture to enable it to be adjustably connected to the 55 member 10 by a bolt or pin 16, as will be obvious. The member 11 is provided with a handle-loop 17 so disposed that when the members are united the handle will come at a substantially central point between the grip- 60 plates. The member 10 is provided with an intermediate recess 25, and engaging the member 10 within this recess, and preferably with a limited oscillatory movement therein, is a catch member 19, having a cavity 20 in one 65 side formed with a depending lip 21 and with the exterior surface 22 inclined. The cavity 20 is to receive the free end 23 of the member 11 to form a readily-detachable coupling means between the members 10 and 11 when 70 no load is being carried, as hereinafter more fully explained.

In operating the device the member 11 is adjusted relative to the member 10 to enable the grip-plates 12 13 to freely pass over the 75 object or objects to be carried—for instance, a number of bricks—as at 24, when the member 11 is depressed and its end 23 inserted into the cavity 20 in the catch 19. By this means the unloaded device can be conveniently carried about by the handle-loop 17, and the latter being centrally disposed the device will be “balanced” when thus transported. In this condition the device can be set down over the requisite number of the bricks and the catch 85 19 released either by turning it to one side by one of the fingers of the hand which grasps the handle-loop 17 or depressing the member 11 and moving it slightly to one side. Then by lifting the device the member 11 is transformed into a very strong gripping-lever, which firmly compresses the bricks between the grip-plates 12 13 and causes them to be lifted with the device and carried to any desired point.

When the load is to be discharged, it is only necessary to set it down where it is to remain and depress the member 11 and insert its end

23 into the cavity 20, which can be readily and quickly accomplished by sliding it over the inclined surface 22 of the catch, when the device can be lifted from its load and carried 5 back for another load.

It will be noted that the whole operation can be performed with one hand, and, if required, one of the devices may be used by each hand, thus doubling the capacity of the 10 operator without inconvenience.

The operator by a very small amount of practice can easily operate the device with one hand only and can transport a much greater quantity of bricks or other goods or material 15 in the same time and with less fatigue than will be possible with other forms of carriers.

In operating the device the movements required to manipulate it are so slight that they will be performed intuitively after using for 20 a short time, and the loads can be picked up, carried to the required point, and there discharged with the expenditure of no more time or labor than would be required to pick up and carry similar-sized loads having permanent handles attached.

As before stated, while the device may be readily adapted for carrying different sizes and forms of objects or groups of objects it is more particularly applicable to the transportation of bricks and similar articles and will 30 be found very convenient for use in kilns, storage-yards, in building operations, and other localities where bricks are to be transported by hand.

35 The device will preferably be of steel as light as may be consistent with the strains to which it will be subjected and may be of any desired size to adapt it to the article to be carried.

40 Having thus described the invention, what is claimed is—

1. A device of the class described comprising two members pivotally united and having oppositely-disposed grips, and a catch carried 45 by one of said members for detachable en-

gagement with the other member when no load is positioned between the grips.

2. A device of the class described comprising two members pivotally united and having oppositely-disposed grips, one of said members having a handle-loop centrally of the united members, and a catch carried by one of said members for detachable engagement with the other member when no load is positioned between the grips. 50

3. A device of the class described comprising two members pivotally united and having oppositely-disposed grips, and a catch carried by one of said members for detachable engagement with the other member when no load is 60 positioned between the grips, said catch member having a limited lateral movement upon the bar on which it is mounted.

4. A device of the class described comprising two members pivotally united and having oppositely-disposed grips, and a catch carried by one of said members and having a cavity for receiving the other member, and inclined exteriorly to guide the member into the cavity. 65

5. A device of the class described comprising two members pivotally united and having oppositely-disposed grips, one of said members having a transverse recess, a catch supported for limited lateral movement in said recess for detachable engagement with the other 70 member.

6. A device of the class described comprising two members pivotally united and having oppositely-disposed grips, and a catch carried by one of said members and formed with a recess terminating in a depending lip to contract the inlet thereto for detachable engagement with the other member. 80

In testimony that I claim the foregoing as my own I have hereto affixed my signature in 85 the presence of two witnesses.

SAMUEL S. LANGFORD.
